UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,144,761.

Specification of Letters Patent. Patented June 29, 1915.

Application filed June 16, 1911. Serial No. 633,573.

To all whom it may concern:

Be it known that I, DAVID W. HAWKSWORTH, a citizen of the United States of America, residing at Detroit, in the county of Wayne and State of Michigan, have invented certain new and useful Improvements in Car-Roofs, of which the following is a specification, reference being had thereto in the accompanying drawings.

10 The invention relates to car roofs of the type in which adjustable supported roofing sheets or plates are weather-proofed by caps embracing flanges on the adjacent sheets, and the invention consists in the peculiar 15 construction of the weather-proofing means as hereinafter set forth.

In the drawings, the figure is a sectional perspective view of a portion of the car roof to which my improvement is applied.

20 A is a carline and B a purlin of the roof frame.

C are roofing sheets or plates extending between carlines and having upstanding edge flanges D. E is a weather-proofing cap embracing the carline and flanges and bearing upon said sheets to form a weather joint therewith.

In certain constructions that have heretofore been used the joint between the cap E and plate C is formed by laterally extending foot flanges on the cap that rests upon sheets. The cap in addition to its function of weather-proofing the joint, also serves to hold the sheet down upon the roof frame, but not to prevent the independent adjustment of said sheet under the weaving and torsional stress produced in the roof frame when the car is in service. Inasmuch as the cap is formed of metal the bearing portion 35 thereof upon the sheet during the relative movement of the parts will cause a rubbing or abrasion of the surfaces which is objectionable. With the present construction the contact of metal to metal is avoided by providing the weather caps with a non-metallic 40 facing which constitutes the bearing on the sheet. Thus as shown, the caps C are provided with laterally extending portions F

above the plane of the roofing sheets terminating in down-turned portions G. In the 50 angle formed by these portions F and G a non-metallic facing H is secured, this being preferably a wooden strip secured by suitable means such as the laterally extending bolts or rivets I engaging the flange G. The 55 strip H will maintain a weatherproofing joint with the surface of the sheet as well as to retain the latter in position upon the car frame, while permitting freedom of movement in the plane of the sheet. This movement will not however, cause any abrasion 60 of the sheet on account of the soft nature of the facing material used.

If desired, a groove J may be arranged to extend longitudinally in the lower face of 65 the strip H so as to form a drainage channel for permitting the escape of any water forcing through the joint between said strip and the sheet.

What I claim as my invention is:

1. In a car roof, the combination with a 70 roof frame, of roofing sheets or plates independently adjustably supported upon said frame, weather-proofing caps for the joint between sheets embracing upstanding flanges 75 of the adjacent edges thereof and constituting a means for holding said sheets down upon the roof frame, and non-metallic facings for said caps forming the bearing upon 80 said sheets.

2. In a car roof, the combination with the 85 roof frame comprising purlins and carlines, of metallic roofing sheets or plates supported on said purlins out of contact with said carlines, caps embracing said carlines and edge flanges on said sheets and forming a 90 means of holding said sheets down upon said purlins, and non-metallic facings for said caps constituting the bearing therefor on said sheets.

In testimony whereof I affix my signature in presence of two witnesses.

DAVID W. HAWKSWORTH.
